UNITED STATES PATENT OFFICE.

JOHN SIDNEY WILLIAMS AND SIDNEY PRESTON WILLIAMS, OF BRISBANE,
QUEENSLAND, AUSTRALIA.

CASEMENT-WINDOW FASTENER AND THE LIKE.

Application filed July 6, 1927. Serial No. 203,701.

This invention relates to fasteners of hinged structures such as casement windows, the fasteners being of the two plate type, one plate being adapted to be secured to the structure and therefore movable with it, and the other plate being securable to an adjacent support, such as the window sill, there being means to hold the movable window plate in any of several positions according to the adjustment of the window desired. Existing fasteners of the type stated so far as known to us have disadvantages, and one object of this invention is to provide fasteners which are easy to instal a place where there is in a right angled area or corner without recessing the framing near the window. Another object is to provide that a pawl carried by the window plate shall engage a selected part either of the fixed plate or of a member—herein called an arm, which is attached to the fixed plate, and which when required becomes an extension in continuation of the fixed plate, so that when the pawl is not in a position to engage the fixed sill plate, it will still be able to engage the extended arm and hold the window more fully open than if the extension were absent. The sill plate has, for a utility hereinafter stated, means by which its front is located with a space between it and the sill.

The applicability of the fixed plate in a right angled corner with the window pivotal line about on the same plane as the surface of a partition extending well inward from the window for example is due to the presence of the extension arm, the window being widely openable. If it be not desired to be able to open the window so widely, the extension arm is omittable.

40 In the drawings herewith, Figure 1 is a plan of an embodiment of this invention applied to a window shown widely open.

Figure 2 is similar to Figure 1, but with the window shown closed.

45 Figure 3 is a front elevation of the parts in Figure 1.

Figure 4 shows in section parts which carry the pawl pivot, enlarged; on line F⁴ of Figure 2.

50 Figure 5 is a plan of the fastener modified, the window being less widely open.

Figure 6 is similar to Figure 5, except that it shows the window closed.

The hinged structure, shown by a window 55 W, is hinged to a frame F which at its base

has a sill S. S¹ denotes the surface of a wall, partition, or fairly deep recess of the window frame. 1 is a window plate, of skeleton and approximately triangular form, fixed in horizontal position to the window 60 fixing screws 1^b being shown extending through suitable parts, shown as lugs 1^a. 2 is a sill plate of skeleton and approximately triangular form fixed with its front spaced over an adjacent support, herein called the 65 sill, for which purpose it has feet 2^a, at its base, one foot at each angle being preferably provided and screwed down, the effect being that under a rail 4 which forms the sill plate a front edge space is left. 70

Each plate 1 and 2 has a front rail, 3 or 4 respectively, the window plate rail 3 being above and coinciding with rail 4 or substantially so when the fastening is closed. Rail 3 may rest on rail 4, and it is glidable 75 above it.

Each rail is curved and the curves have, as a centre, the axis of the window hinge H, so that the rails continue to coincide but to a decreasing extent while the window is being opened, until a point is reached when the window rail has moved quite past the sill rail. The window plate rail 3 has a lug 3^a which when the window is closed or sufficiently so, overhangs the front edge of the 80 sill rail 4. This lug carries a pawl 5 and to facilitate this, a boss 3^b is provided on the lug. The boss is apertured to receive the pawl pivot pin 5^a, and the aperture interior 3^c is dimensioned to house part of a suitable spring 5^b, ends of which are indicated in dotted lines at 5^c, Figure 1. The pawl 5 has a tooth 6 which is so urged by the spring that the tooth end bears on the sill rail 4 and normally engages one of a series 90 of recesses therein, shown as notches, 4^b, 4^c, the rail end 4^a being also adapted for tooth engagement to hold the window fastened in closed position.

The building may have a wall, framing or partition surface S¹ at right angles to the closed window so that there is not space for the rail end 3^a to be moved inwardly beyond that wall or like surface when the window is closed, see Figures 4 and 5. 100 Therefore the length of the rail 3 having the end 3^a is limited in this invention accordingly, although the rails of certain prior fasteners have not that limitation. The right angled corner area shown in the drawings 110

is bounded by the window and by the adjacent framing S^1 , and is over the sill end. The extremity 3^d of rail end 3^a , does not extend beyond surface S^1 .

5 An arm 7, pivoted to rail 4 is provided as shown in Figures 1 to 3. This arm moves on its pivot 7^a from its normal closed position shown in Figure 2, into its open position shown in Figure 1, when the window is being opened, such opening causing the pawl tooth 6 to strike and to press a point 7^b of arm 7.

When the widely opened window is being closed, it approaches the extension arm, and eventually reaches the outer end 7^c of that arm. That end is suitably formed, being shown rounded. The said end on being pressed by the window, causes the arm to swing inwardly to the position of Figure 2. This extension member is recessed to receive the pawl tooth end, notches being shown in its edge, at 4^d and 4^e .

When it engages the end 4^e , tooth 6 fastens the window in closed position; by engaging any recesses 4^b , 4^c or 4^d , it holds the window partly open; and by engaging recess 4^e it holds the window very widely open. The length of the extension arm is not necessarily limited to that illustrated.

10 The extension arm is formed with a stop 10 shown on its underside and when the window is widely opened the pawl extended end 6^a of pawl tooth 6 is arrested by the stop, which then prevents excessive opening of the window. In Figure 5 a stop is provided on the sill plate and is shown at 10^a on the underside thereof, as an alternative to stop 10.

15 Finger lugs 8, 9 project from rail 3 and pawl 5 respectively, and are normally spaced a short distance apart by the influence of the pawl spring 5 b . The extended end 6^a of tooth 6 being below the rail 4 prevents rail 3 lifting from its normal position close above rail 4.

20 By pressing this pair of lugs together, between a finger and thumb for example, the pawl tooth 6 is detached from any recess it engages, and the operator, while still gripping the lugs together, pushes them in any direction he wishes and thus pushes the window to any position he desires. When that position is reached he releases the lugs, allowing the pawl tooth to spring an adjacent recess and hold the window firmly.

25 An extension arm can be dispensed with as in Figures 5 and 6, if without such arm, the window opens sufficiently wide for use; in these figures the triangular plates have each an acute angle opposite the curved rail. Such an angle is useful only occasionally that is when it is desirable to further economize the space the fastening occupies.

30 When the window plate has been fitted, its position enables the sill plate to be easily

and correctly located, so that when the window is closed the front rails of the plates will substantially coincide and so that the sill plate will prevent sagging of the window relatively to its hinge H.

70

We claim:—

1. In a fastening for a hinged structure, two plates one to be fixed to said structure, the other to be fixed to an adjacent support, a pivoted pawl on one plate, and on the other plate recesses to be engaged by said pawl, the latter plate supporting a pivoted extension arm recessed for similar engagement, said arm shifting into extended position in continuation of its supporting rail by opening 75 the hinged structure beyond a predetermined extent, and shifting into closed position by closing the said structure.

2. The construction in claim 1, but wherein each plate has a curved front rail, the rails 80 substantially coinciding when the fastening is closed, the curves having the same axis, one rail being recessed for pawl engagement, the other rail having the pawl pivoted to it with spring means to cause said engagement. 85

3. The construction in claim 1, but wherein during window opening the pawl strikes the extension arm and shifts it into extended position. 90

4. The combination with a window plate having a curved front rail carrying a spring urged pawl, of a sill plate to be fixed to an adjacent support and having a curved front rail close to and below the window plate 100 rail, an extension arm pivoted to the sill plate, recesses in the sill plate rail and in the said arm to be engaged by the pawl, a finger lug on the window plate rail and a finger lug on the pawl, the lugs being adapted to be held pressed together to free the pawl, and while so held pushed in any direction by which to move the window, said arm shifting when struck and pushed, either by the pawl or window. 105

5. A sill plate having a front curved recessed rail having pivoted to it a recessed extension arm adapted to be swung into extended or closed position, in combination with a window plate having a curved front 115 rail having a finger lug and also a projecting lug carrying a spring urged pawl having a finger lug, and having a toothed projection for recess engagement.

6. The construction as claimed in claim 1, 120 in which each plate has a curved front rail and the fixed plate is provided with under projections to locate its front rail and its extension arm over a space which is over the support of said projections, and the pivoted pawl having an extension which enters and is movable along the said space. 125

7. In combination with a hinged structure and an adjacent wall forming therewith an angular area, an upper plate fixed to said 130

structure, and a lower plate fixed to an adjacent support, the area of each plate being less than that of the angular area, a corner at the inner end of the lower plate being located at a distance from the wall, the lower plate carrying a pivoted extension arm adapted to be swung into open position beyond the fixed lower plate by the movement of a pawl on the upper plate beyond said fixed plate, the pawl being adapted to engage the said inner corner of the

lower plate between it and the wall to hold the said hinged structure in closed position, the pawl being adapted to engage one of a series of notches in the lower plate, or in the 15 said extension, to hold the structure in an open position.

In witness whereof we have hereunto set our hands.

JOHN SIDNEY WILLIAMS.
SIDNEY PRESTON WILLIAMS.
